COOKING UTENSIL HANDLE COVER

Fannie Raphiel Arnone, Kansas City, Mo.

Application July 20, 1950, Serial No. 11,275

Term of patent 14 years

(Cl. D44—29)

To all whom it may concern:

Be it known that I, Fannie Raphiel Arnone, a citizen of the United States, residing at Kansas City, in the county of Jackson and State of Missouri, have invented a new, original, and ornamental Design for a Cooking Utensil Handle Cover, of which the following is a specification, reference being had to the accompanying drawing, forming a part thereof.

Fig. 1 is a perspective view of a cooking utensil handle cover, showing my new design.

Fig. 2 is a side elevational view thereof; and Fig. 3 is an edge elevational view thereof.

I claim:

The ornamental design for a cooking utensil handle cover, as shown.

FANNIE RAPHIEL ARNONE.
